UNITED STATES PATENT OFFICE.

CHARLES F. LEMCKE, OF MILWAUKEE, WISCONSIN, ASSIGNOR OF ONE-HALF
TO JOSEPH MILBAUER, OF MILWAUKEE, WISCONSIN.

FLOOR-RUBBER.

SPECIFICATION forming part of Letters Patent No. 702,569, dated June 17, 1902.

Application filed March 4, 1902. Serial No. 98,688. (No model.)

To all whom it may concern:

Be it known that I, CHARLES F. LEMCKE, a citizen of the United States, and a resident of Milwaukee, in the county of Milwaukee and 5 State of Wisconsin, have invented certain new and useful Improvements in Floor-Rubbers; and I do hereby declare that the following is a full, clear, and exact description thereof.

The improvements consist in what is hereinafter particularly set forth with reference to the accompanying drawings and subsequently claimed, the object of the invention being to provide simple, economical, and labor-saving implements especially designed 15 for oiling hard-wood floors, but which may be utilized for other operations on oiled or waxed floors.

Figure 1 of the drawings is indicated by lines 1 1 in the third figure of the series and 20 represents a partly-sectional side elevation of an implement in accordance with my invention; Fig. 2, a rear elevation of the implement, partly broken and in section, this view being indicated by line 2 2 in the third figure; and Fig. 3, a plan view of a fragment of said implement, partly in horizontal section, this view being indicated by line 3 3 in the first figure.

Referring by letter to the drawings, A indicates a flat block of wood or other suitable material, that is preferably longer than wide and rounded at the corners. This block is shown provided with a longitudinal slot b, and a correspondingly-slotted pad B, of felt 35 or other suitable material, is made fast to the under side of said block by any suitable means, the block and pad slots b c being in register:

A gutter C, of sheet metal or other suitable 40 material, is arranged in connection with block A to engage the slot of same and slot c of pad B, this gutter being provided with an upper rearwardly-inclined extension D, that constitutes a shield, for the purpose hereinafter 45 specified.

Back of shield D is a similarly-inclined socket E, made fast to block A, and a handle F is stepped in the socket.

A series of independent spring-clips G, each

fast at one end on the upper face of block A, 50 adjacent to the rounded corners of same, serve as means by which to clutch and hold a pad-facing cloth H, that is drawn on said block over the upper edges of same, the pad-slot c being closed by the cloth. Each 55 clip G is a single bent plate of spring metal, made fast at one end on the top of block A, the other or free bent end of the plate being pointed in opposition to the block.

A pair of parallel standards I, mounted on 60 the block, have their upper ends provided with open curved slots d, engaged by trunnions J, that extend from heads of a cylindrical reservoir K eccentric thereto, whereby preponderance of weight of the reservoir is 65 below its trunnions, and an apertured closure L is provided for a normally upper filling-nozzle of said reservoir. In connection with a normally lower eye M, extending from the reservoir, is a cord N, that extends partly 70 around said reservoir forward of same and is carried back and made fast to an eye P, with which the handle F is provided, at a point within convenient reach of an operator of the implement. By pulling on the cord 75 the reservoir is turned to bring its outlet (the aperture in nozzle-closure L) over the gutter C, and oil or other fluid from said reservoir finds its way to cloth H to saturate the same. On release of the cord the reservoir automatically rights itself, and in either direction of movement on the part of said reservoir the shield D intercepts fluid that would otherwise fall on the block A, this fluid being deflected 80 into the gutter C aforesaid. To limit the throw of the reservoir when cord N is pulled, a lug Q is arranged in connection with a head 85 of said reservoir to come in contact with a rear edge of one of the standards I at the time the fluid-outlet is in register with the 90 distributing-gutter.

The implement is pushed about over a floor to rub oil therein, the oil being supplied to the spreading and rubbing cloth as often and in such quantity as may be necessary or desirable. Whenever a cloth becomes unserviceable a new one is substituted, and while I have shown a reservoir that is rotary adjust- 95

able to feed oil therefrom to the cloth I do not wish to be understood as limiting myself to this construction.

The implement may be utilized without oil 5 to polish previously oiled or waxed hard-wood floors or for cleaning the same with spirits of turpentine or other fluid suitable for the purpose.

Having thus described my invention, what 10 I claim as new, and desire to secure by Letters Patent, is—

1. A floor-rubber comprising a block having a handle, a pad on the under side of the block, a pad-facing cloth drawn on the block 15 over the upper edges of same, and cloth-holding spring-clips each consisting of a single bent plate of spring metal made fast at one end on the top of said block and having its other or free bent end pointed in opposition 20 to the same.

2. A floor-rubber comprising a slotted block having a handle, a slotted pad on the under side of the block, the pad and block slots being in register; a removable pad-facing cloth 25 drawn on said block over the upper edges of same, means by which the cloth is detachably held in place, a reservoir suspended over the aforesaid block, and means for regulating feed of fluid contents of the reservoir to 30 said cloth through the block and pad slots.

3. A floor-rubber comprising a slotted block having a handle, a slotted pad on the under side of the block, the pad and block slots being in register; a gutter engaging said slots

and provided with a rear shield extension, 35 standards on the block, a reservoir in trunnion connection with the standards and having preponderance of weight below its trunnions, a pull-cord arranged in connection with the reservoir to turn the same toward the rear 40 and bring a normally upper outlet thereof over the gutter, a pad-facing cloth, and means in connection with said block for holding the cloth in place.

4. A floor-rubber comprising a slotted block 45 having a handle, a slotted pad on the under side of the block, the pad and block slots being in register; a gutter engaging the slots and provided with a rear shield extension, standards on the block, a reservoir in trunnion connection with the standards and having preponderance of weight below its trunnions, a pull-cord in connection with the reservoir to turn the same toward the rear and bring a normally upper outlet thereof over 50 the gutter, a standard opposing stop-lug extending from said reservoir to limit rotary adjustment of same by the cord, a pad-facing cloth, and means in connection with said block for holding the cloth in place.

In testimony that I claim the foregoing I have hereunto set my hand, at Milwaukee, in the county of Milwaukee and State of Wisconsin, in the presence of two witnesses.

CHAS. F. LEMCKE.
